ASH TRAY

John Gottfried, Newark, Ohio

Application May 21, 1949, Serial No. 2,793

Term of patent 3½ years

(Cl. D85—2)

To all whom it may concern:

Be it known that I, John Gottfried, a citizen of the United States, residing at Newark, in the county of Licking and State of Ohio, have invented a new, original, and ornamental Design for an Ash Tray, of which the following is a specification, reference being had to the accompanying drawing, forming part thereof.

Figure 1 is a plan view of an ash tray showing my new design.

Figure 2 is an edge view of the same.

The bottom of the instant ash tray is substantially plain.

I claim:

The ornamental design for an ash tray, substantially as shown and described.

JOHN GOTTFRIED.
